UNITED STATES PATENT OFFICE.

ORIEN R. SMITH, OF ATHENS, MICHIGAN.

DISK HARROW.

SPECIFICATION forming part of Letters Patent No. 623,575, dated April 25, 1899.

Application filed November 11, 1897. Serial No. 658,125. (No model.)

To all whom it may concern:

Be it known that I, ORIEN R. SMITH, of Athens, county of Calhoun, and State of Michigan, have invented certain new and useful Improvements in Disk Harrows; and I do hereby declare that the following is a full, clear, and exact description of the invention, which will enable others skilled in the art to which it appertains to make and use the same, reference being had to the accompanying drawings, and to the letters and figures of reference marked thereon, which form part of this specification.

This invention relates to harrows; and the object of the invention is to provide a harrow which by means of rotary disks or diggers may move the earth transversely, as well as stir the soil.

A further object is to improve various parts and combinations of mechanisms used with rotary or disk harrows and the draft mechanism thereof to enable the machine to vary the action of the disks either in direction of movement or amount of entry into the ground and to place the operation of the disks under control of the operator.

Figure 1 is a top plan of a harrow according to my invention, parts being broken away. Fig. 2 is a side elevation of harrow also showing how seeding attachments may be connected thereto. Fig. 3 is a detail cross-section through the bearing-pivots of the disk-axes and frame. Fig. 4 is a detail elevation, and Fig. 5 a detail longitudinal section, of the axle, bearing, and connections. Fig. 6 is a detail section, and Fig. 7 an elevation and partial section, of axle and link connections. Fig. 8 is a perspective view of the mud-cleaner. Fig. 9 is an elevation and partial section of link-lifting mechanism. Fig. 10 is a detail longitudinal section of rear axle at the universal joint.

The parts constituting the front axle are indicated at 1 and 2, and the parts of the rear axle are indicated at 3 4 of the drawings. These axles are preferably polygonal in cross-section, the form shown being square, and are of strong metal, and saucer-shaped rotary diggers 5, usually called "disks," are mounted on the axles, so as to turn with the axles.

Between these disks short spacing sleeves or tubes 6 may be interposed, the sleeves surrounding the axles and having their ends

bearing against the so-called "disks." These spacers are preferably smallest in outer diameter at their central portions and enlarged 55 toward their ends.

Numerals 11 and 12 designate frame-bars, which are connected by a cross-bar 65, forming an H-shaped frame. The axles are mounted in bearing-boxes or supports 7 8 9 10, and these boxes are pivotally connected to the frame, so as to allow vertical and lateral movement to the axles, the shafts being preferably supported by ball-bearings. Short spacers or sleeves 13 16 on the rear axle inside the frame-bars and short sleeves 14 15 on the front axle outside the frame-bars surround the axle and support the disks thereon. The cross-bar 65 is pivotally connected to the frame-bars 11 12, as indicated at 66, so that 70 the longitudinal bars may have independent movement.

The axles pass through collars or hub-sections 56 57, which collars are connected by a threaded connection 58. (See Fig. 5.) These 75 collars 56 and 57 thus form a hub through which the axle may move longitudinally, but the hub must turn with the axle. The collars or hub-sections 56 57 have bearing-surfaces for balls 59, and can be set up more or 80 less toward each other, and inclose the balls 59 in the bearing-sleeve 55, the sleeve having corresponding bearing-surfaces. This bearing-sleeve 55 is supported by pivots 63, which project through swivel-pieces 51, the swivel-pieces being suspended from frame-bars 11 85 12. (See Fig. 3.) Dust-guards 61 exclude dirt from the ball-bearings by covering-joint 62, between the hub and sleeve.

The frame-bars 11 12 are shown in Fig. 2 90 as arched in the direction of their length. From the lower faces of these arched bars the brackets *a* extend downward, one at each corner of the frame. These brackets *a* have pintles 52 at their lower ends, and the swivel-pieces 51 are mounted on these pintles and held by nuts *d*, the abutting shoulders 53 54 permitting a swivel movement of the piece 51. Thus the axles are mounted in bearings which permit a universal movement or adjustment to the axles. 95 100

The front axles 1 and 2 are substantially in line with each other. The adjacent ends of the axles are provided with convex bear-

ing-pieces 17 18, so that the end thrust of these axles or shafts will be communicated from one of these axles to the other, while otherwise independent movement of the axles 5 will be permitted.

The rear axles 3 and 4 are connected to each other by a ball-and-socket connection. (See Fig. 10.) Concavo-convex disk 43 is connected rigidly to one axle-section, and a reverse concavo-convex piece 44 is secured to disk 43, and an opening 45 is formed therein. A plate 50, between parts 43 44, holds the shaft-section 49, and a ball 48 at the end of this section rests in socket 47, which socket is in collar 46, secured to axle 3. Thus the rear axles are connected by ball-and-socket joint.

The disks 5 on the front axle at each side of the central part of the frame are arranged with their concave faces outwardly. The 20 disks will thus tend to throw the soil outwardly as the harrow is drawn over the ground, especially when the axles are properly inclined, and, conversely, the axles 1 and 2 will tend to thrust toward the longitudinal center of the frame. Thus the axles counter-balance each other. The disks 5 on the rear axle have their convex faces outward, and therefore when properly adjusted tend to throw the earth inward and balance each 30 other by pulling on the ball-and-socket joint.

The rear axles 3 4 are together longer than the front axles 1 and 2, and the disks on the rear axles are behind the intervals between the disks on the front axle, so that the rear 35 disks do not follow in the track of the front disks. As shown, the rear axles have each two disks and the front axles each one disk outside the longitudinal frame-bars.

Mounted on the tongue or central bar 34 40 are two levers 20 21, these being pivoted to brackets 22. From the lower end of lever 20 links 23 extend forward, and from the lower end of lever 21 links 23 extend rearwardly, and each of these links is connected to its lever and to a sleeve, as indicated at 24 25 26 45 27, these sleeves being mounted on the axles and turning in sockets *b*, which are connected to the links. Levers 20 21 may be held by catches engaging in plates 33 in usual manner. Thus by rocking lever 20 the inner ends of axles 1 2 may be inclined in either direction from a transverse line, and axles 3 4 may be manipulated in similar manner by lever 21, such movement of the axles being permitted by the universally-movable bearings 50 before described. This inclination of the axles will cause the disks to work a wider or narrower belt of soil and to throw it more or less back and forth in lateral direction. 60 When the axle-sections have been adjusted to any desired angle, the levers 20 21 are secured by their catches, and thus hold the axle-sections until the levers are again moved.

Brace-bars 30 extend transversely of the 65 frame, being connected to bars 11 12 in any suitable manner. Sockets 29 on these braces receive vertically-movable bars 28, which

bars straddle the links 23 and are connected thereto. Springs 31 surround bars 28 above and below braces 30 and are held in position 70 by heads or nuts *c* on the bars 28. By the adjustment of nuts *c* the bars 28 may be raised or lowered and with them the links 23 23, thus raising or lowering the inner ends of the axles, producing a corresponding reversal of position of the outer ends. Brace-bars 32 75 strengthen and stiffen the construction and are adjustably connected in usual manner to permit the adjustments stated. The joints and connections are constructed to give some 80 flexibility, as usual in machines of this character. The adjustment of nuts *c* thus adjusts the axles so that either the outer or inner disks may enter most deeply into the soil or all may be at uniform height. The pivot 85 of one lever 20 21 works within a tubular sleeve forming a pivot for the other lever, as is common.

Fig. 8 shows the scrapers, which may be applied to clean mud from the disks when land 90 is wet or sticky. Transverse bars 41 extend in direction about parallel with the axles, being supported from the journals of the axles. From these bars 41 the scrapers 33' extend in rather close proximity to the concave sides of 95 the disks 5. A foot-lever 35 on the tongue is connected by links 39 to arms 40, which arms are secured to bars 37 and 38, extending from front to rear of the harrow. Bars 37 and 38 are connected to springs 42, which springs are 100 connected to bars 41, so that a shifting of lever 35 will cause the scrapers to bear with a yielding pressure on the disks, or, at least, will pull the scrapers toward the disks. The bars 41 are supported from the axle-bearings by 105 standards 64, which are connected to swivel-pieces 51 by the pins or pintles 63, as shown in Figs. 3 and 4.

The tongue 34 extends back far enough to 110 form a support for the levers hereinbefore referred to, and extends forward as far as may be needful. A lever 71, pivoted to a slide on the tongue, is connected to the bars 11 12 by suitable braces *e e*. On the tongue are slide-ways 67 68 69, and in these ways are slides to 115 which the levers 70, 71, and 72 are pivoted. The pivots of levers 70 71 are connected by a rigid link *f*, so that these levers move forward or backward together, but may rock independently. 120

The lever 72 serves as a means for attachment of the team by suitable trees, a double-tree being shown at one side of the tongue and a singletree at the other side. Long arm of lever 72 is connected to short arm of lever 125 70 by link 73, and long arm of lever 70 is connected to short arm of lever 72 by link 73', and lever 70 is connected to lever 71 by rigid link or bar *f*. The pull of the team is thus equalized, and the equalizing-lever is connected to both side bars of the frame, as has been explained. The entire frame is thus given great flexibility, as well as strength. 130

By the construction described a disk har-

row is produced which has flexibility to adapt it to irregular or unequal surfaces and which may be adjusted to various conditions of the soil and to overcome and reduce inequalities of surface to a greater extent than any harrow with which I am acquainted.

I have shown the machine as having the greater number of disks on the rear axles; but of course this might be varied, and I contemplate modifications within the limit of my claims.

In Figs. 1 and 2 I show how a seeding attachment may be connected to my harrow, said seeding attachments being indicated at 15 74, 75, 76, 82, 87, 95, and 96; but as such has been held to be a separate invention I do not herein describe and claim said seeding attachment.

What I claim is—

- 20 1. In a disk harrow, disks mounted upon separate axles, pivotally secured to segmental frames, a tongue pivotally secured thereto, and means for adjusting the depth of cultivation.
- 25 2. In a disk harrow, disks mounted upon axles adapted to move vertically and horizontally, varying spacers interposed between the disks, allowing for horizontal diverging or converging movement of the axles in ball-bearing hubs, a sectional frame pivotally secured to the hubs adapted to reciprocate in conformity to undulations of the field, means for controlling the disk-axles, and a disk-cleaner.
- 30 3. In a disk harrow, disks spaced upon movable axles pivotally secured to a segmental frame, a tongue, locking and adjusting levers pivoted to the tongue adapted to control the angular adjustment of the disk-axle, means for counteracting the thrust and tension of the axles, cross-ties securing the segmental frames, vertical adjustable and spring-actuated rods secured to the cross-ties to control the vertical elevation of the axles, a plurality of levers which equalize the draft secured to 45 the tongue.
- 35 4. In a disk harrow, a plurality of disks mounted and spaced upon axles adapted to move independently, and pivotally secured by ball-hubs to a segmental frame, mud-guards protecting the ball-hubs, a tongue pivotally secured to the segmental frame, spring-actuated cleaners movably in contact with the disk, and a foot-lever pivoted upon the tongue for retracting the cleaners.
- 40 5. A disk harrow having longitudinal frame-bars at its sides, flexibly connected to each other, and independent axle-sections having yielding bearings in said frame-bars and extending transversely of the frame, the adjacent ends of these axles having thrust-pieces, and disks mounted on said axle-sections, all combined substantially as described.
- 45 6. In a disk harrow, a flexible frame, an axle in sections having end-thrust pieces to bear on each other, yielding bearings, and means for adjusting the axle-sections separately to an angle from the transverse direc-

tion and disks on said axle, substantially as described.

7. In a disk harrow, a flexible frame, an axle in sections and having yielding bearings, disks on said axle, and means for vertically adjusting the proximate ends of the axle-sections, whereby the axle-sections are placed out of horizontal alinement, substantially as 75 described.

8. In a disk harrow, a flexible frame having supporting standards, swivel-pieces connected to said standards, bearing-boxes pivotally supported within the swivel-pieces, the 80 axle-sections in said bearings having disks thereon, and means for adjusting said axle-sections, all combined substantially as described.

9. In a disk harrow, a flexible frame, bearing-boxes movably supported thereon, hub-sections in said boxes having interposed bearing-balls, axle-sections longitudinally movable in said hub-sections, and disks on the 85 axle-sections, all combined substantially as 90 described.

10. In a disk harrow, a flexible frame, disks on axle-sections independently adjustable in said frame, and an equalizing-lever on the tongue and independently connected to different parts of the flexible frame, all combined.

11. In a disk harrow, the frame composed essentially of two longitudinal bars, a transverse bar pivotally connected to the longitudinal bars, and transverse axles in sections, 100 each section supported in a universal bearing connected to one of the longitudinal bars, all combined substantially as described.

12. In a disk harrow the adjustable hub-sections provided with bearings for balls, the 105 sleeve having corresponding bearing-surfaces, the pivotal supports by which said sleeves are connected to the frame, the bearing-balls, and the axle-section having harrow-disks thereon, all combined substantially as 110 described.

13. The arched frame-bars having pendent brackets provided with pintles at their lower ends, swivel-pieces mounted on these pintles, and the axle-sections movably supported by 115 these swivel-pieces, all combined substantially as described.

14. In a disk harrow, the frame having longitudinal bars, the transverse axle-sections carrying disks and mounted to have universal 120 movement on the frame-bars, a lever on the frame, and means connecting said lever to the axle-sections so that the same may be adjusted out of transverse position, substantially as described.

15. In a disk harrow, the frame having longitudinal bars, the transverse axle-sections supported in the universal bearings on said bars and carrying disks, and vertically-adjustable connections to the frame by which 130 one end of an axle-section may be vertically adjusted, so the axle-sections will not lie in the same plane, all combined substantially as described.

16. In a disk harrow, a frame, the axle-sections supported in universal bearings on said frame and carrying disks, scrapers supported from the axle-bearings and maintaining the general directions of the disks, and means whereby the scrapers may be adjusted by the operator, all combined substantially as described.
17. In a disk harrow, the flexible frame having longitudinal bars, the axle-sections universally adjustable and connected to said

frame-bars, and carrying the disks, and the equalizing-bar connected to the draft mechanism and to the longitudinal bars of the frame, all in combination.

In testimony that I claim the foregoing as my own I hereby affix my signature in presence of two witnesses.

15 ORIEN R. SMITH.
